PHONOGRAPH AND LOUDSPEAKER CABINET

Melvin H. Best, Pasadena, Robert K. Fujioka, Los Angeles, and William J. Ward, Monterey Park, Calif., assignors to Ampex Corporation, Redwood City, Calif., a corporation of California

Application November 28, 1956, Serial No. 43,978

Term of patent 14 years

(Cl. D56—4)

FIG. 1—

FIG. 2—

FIG. 3—

Figure 1 is a perspective view of a combined phonograph and loudspeaker cabinet, showing our new design;

Figure 2 is a side elevational view; and

Figure 3 is a perspective view of the design showing a front drawer in partially open position and showing a cover lifted and folded back.

We claim:

The ornamental design for a phonograph and loudspeaker cabinet, as shown.
